UNITED STATES PATENT OFFICE.

FREDERICK H. FURNISS, OF WATERLOO, ASSIGNOR OF ONE-HALF TO MARSHALL A. HUDSON, OF SYRACUSE, NEW YORK.

OIL-CAN.

SPECIFICATION forming part of Letters Patent No. 239,241, dated March 22, 1881.

Application filed January 8, 1881. (Model.)

To all whom it may concern:

Be it known that I, FREDERICK H. FURNISS, of Waterloo, in the county of Seneca, in the State of New York, have invented new and useful Improvements in Oil-Cans, of which the following, taken in connection with the accompanying drawings, is a full, clear, and exact description.

The object of this invention is to provide an oil-can which shall prevent evaporation of its contents and guard against explosion of same; and it consists in a peculiar construction of a stopple and its connection with the inlet-tube, whereby said stopple is prevented from becoming lost, readily applied to and removed from the inlet-tube, and when applied it effectually prevents the escape of gas from the can.

In the accompanying drawings, Figure 1 is a side view of my improved oil-can, the dotted line showing the stopple removed from the inlet-tube. Fig. 2 is a vertical section of same, and Fig. 3 a detail view of the stopple.

Similar letters of reference indicate corresponding parts.

A represents an oil-can of any ordinary shape and dimensions.

s is the spout for the discharge of the oil. This spout I extend down the interior of the can, and terminate it with an open end at or near the bottom thereof, as illustrated in Fig. 2 of the drawings. The upper extremity passes through the top of the can, and its protruding discharge end is of the usual form.

It will be observed that by the extension of the spout to the vicinity of the bottom of the can I prevent the escape of the gas, which usually rises to the surface of the oil and accumulates in the upper part of the can, and consequently prevent evaporation of the oil and avoid the danger of explosion.

a denotes the inlet-tube, through which the oil is introduced into the can. b is the stopple for said inlet. This stopple I form with a suitable head or handle, h, for the manipulation of same, and with a flange or an enlarge-

ment, f, by which it is seated upon the end of the inlet-tube a. Under the enlargement f the stopple has a tapered or conical extension adapted to enter the inlet-tube, and at 50 the junction of this tapered portion with the enlarged portion f it is provided with an annular groove, e, in which is inserted a gasket or packing-ring, c, of rubber or other suitable material, said gasket being sufficiently wide 55 to extend over the top edge of the inlet-tube and form an air-tight seat for the enlarged portion f of the stopple. The exterior of the inlet-tube a is surrounded by a spiral spring, s', which has its upper end firmly attached to 60 the tube a, and with its lower end exerts a downward pressure on a ring, g, which, by a bail, n, is connected with the head or handle of the stopple, and thus holds the same seated upon the top of the inlet-tube. When it is 65 desired to open the said inlet the top of the stopple can be pressed or tilted to one side, as shown by dotted lines in Fig. 1 of the drawings. In replacing the stopple the groove e engages the top edge of the inlet-tube, and 70 serves as a fulcrum for carrying the top of the stopple over and onto the said tube.

Having described my invention, what I claim is—

1. The combination, with an oil-can, of the 75 inlet-tube a, stopple b, gasket c, ring g, spring s', and bail n, substantially as shown and described.

2. In combination with the inlet-tube a, the stopple b, provided with the annular groove 80 e and gasket c, bail n, ring g, and spring s', substantially in the manner and for the purpose specified and shown.

In testimony whereof I have hereunto signed my name and affixed my seal, in the presence 85 of two attesting witnesses, at Syracuse, in the county of Onondaga, in the State of New York, this 31st day of December, 1880.

FREDERICK H. FURNISS. [L. S.]
